PULSE ANALYZER

William E. Glenn, Jr., Birmingham, Ala., assignor to the United States of America as represented by the United States Atomic Energy Commission

Application January 14, 1949, Serial No. 70,865

5 Claims. (Cl. 235—92)

1

This invention relates to a method and apparatus for analyzing pulses of voltage and more particularly to an apparatus for sorting and counting pulses of voltage at predetermined amplitudes.

Pulse analyzers have been developed employing intricate circuits employing a plurality of biased discharge tubes. The inherent characteristics of such discharge tubes introduce errors because of drift which necessitates recalibration each time the analyzer is used. Other disadvantages with such pulse analyzers are their inability to count pulses having a short duration and their sluggishness of operation. The present invention uses an electron gun arrangement similar to that of a cathode ray tube for producing an electron beam, the deflection of which is controlled by the input voltage pulses. The pulse height selecting circuit is simple and free from errors due to tube characteristics and provides a simple and rapid method of determining the number of voltage pulses occurring between two predetermined amplitudes.

It is therefore an object of the present invention to provide a new and improved pulse analyzer.

A primary object of the present invention is to provide a pulse analyzer which is capable of handling pulses of very short duration and which operates in an extremely fast manner.

Another object of the present invention is to provide a pulse analyzer characterized by its simplicity and accuracy.

A further object of the present invention is to provide a pulse analyzer which counts pulses of voltage having the same amplitude over a large range of amplitudes.

A still further object of the present invention is to provide a new and improved method of sorting and counting pulses of voltage having the same amplitude for a large variation of peak voltages.

Another object of the invention is to provide a pulse analyzer employing a modified cathode ray type tube for counting pulses of the same amplitude.

Other objects and advantages will be apparent in the following description considered together with the accompanying drawing in which the present invention is shown in schematic form.

Considering the drawing in detail, there is shown a substantially conical envelope 11 diverging into a flanged portion 12. A cover plate 13 made of a nonconducting material, such as hard rubber, is fastened by bolts 14 to the flange

12. In order to make an airtight seal between the cover plate 13 and the flange 12, a washer 16 of rubber or similar material is provided therebetween. A plurality of targets 17 is mounted centrally in a linear spaced-apart and staggered array along the length of the cover plate 13 and each of the targets 17 has an electrically conducting lead 18 brought out through a vacuum seal type connector (not shown) in the cover plate 13. An electron gun arrangement is disposed axially at the other end of the envelope 11 and comprises a heater filament 19, a cathode 21, a control grid 22, a focusing electrode 23, an accelerating electrode 24, a pair of deflecting plates 26 and 27, and a pair of vertical deflecting plates (not shown).

A source of electrical pulses 28, such as an ionization chamber, is connected by two wires 29 and 31 to a pulse amplifier 32. The output voltage of the pulse amplifier is connected by two leads 33 and 34 to a discriminator 36 and by a wire 37 to the deflecting plate 26 through a vacuum seal 38 in the envelope 11. The output voltage of the discriminator 36 is connected between the cathode 21, by a lead 41, and the control grid 22, by a lead 42, for supplying a gating voltage thereto. The leads 41 and 42 are connected through the envelope 11 by means of vacuum seals 43 and 44 respectively.

For supplying operating voltages to the elements of the electron gun a power supply 46 is provided. A heater voltage is connected from a pair of terminals 47 and 48 of the power supply 46 by two leads 49 and 50 to the filament 19 through vacuum seals 51 and 52 respectively in the envelope 11. Another terminal 53 supplies a common connection for the other voltages of the power supply 46 and is connected by a lead 54 to the cathode 21. An accelerating voltage is connected from a terminal 56 of the power supply 46 by a wire 57 through a vacuum seal 58 in the envelope 11 to the focusing electrode 23. The power supply 46 furnishes an accelerating voltage to the accelerating electrode 24 by a lead 61 connected between the accelerating electrode 24 and a terminal 62 on the power supply 46 through a vacuum seal 63 in the envelope 11. A further voltage is connected from a terminal 66 of the power supply 46 by a wire 67 through a vacuum seal 68 in the envelope 11 to the deflecting plate 27. For vertically centering the electron beam the vertical deflecting plates (not shown) may be connected in a conventional cathode ray tube manner to a suitable source of unidirectional power.

The leads 18 connected to the plurality of targets 17 are each connected to individual amplifiers 71, the output voltages of which are connected to a like number of mechanical registers 72 by leads 73.

Prior to operation of the present invention, it is necessary to assemble the electron gun elements within the envelope 11, bolt the cover plate 13 carrying the targets 17 to the flange 12 with the rubber washer 16 as an airtight seal therebetween, and evacuate the resulting chamber formed. Then with the connections between the electron gun elements and the power supply 46 made, as previously described, the power supply 46 is energized. Under these conditions the filament 19 becomes heated, thereby rendering the cathode 21 electron-emissive. Since the control grid 22 has no potential applied, the focusing electrode 23 is positive with respect to the cathode 21, and the accelerating electrode 24 is positive with respect to the focusing electrode 23, the electrons emitted at the cathode 21 are attracted away from the region of the cathode 21, focused by the focusing electrode 23, and accelerated by the accelerating electrode 24. The electrons thus accelerated through the positive electric field of the accelerating electrode then pass through the electric field of the deflecting plate 27. The potential applied to the deflecting plate 27 is negative to curve the electrons away from the plate 27 and should be adjusted so that the electron beam impinges at a point "X" adjacent the end target 17 which is the furthest from the deflecting plate 27.

The next step is to connect the targets 17, as described hereinbefore, to the mechanical registers 72 through the amplifiers 71. Under this condition, it is a simple matter to determine the values of voltage necessary to cause a deflection of the electron beam so that each counter will be operated by connecting a variable power supply (not shown) to the deflecting plate 26 and noting the voltage at which each register 72 operates. These values of voltages may be calculated with a fair degree of accuracy, since the accelerating voltage and tube dimensions are known; however, calibration with a variable power supply is preferable.

Now, with the foregoing adjustment and calibration accomplished, the remaining connections, as described in the foregoing paragraphs, should be made. The discriminator 36 is so constructed that the control grid 22 of the electron gun is normally biased with a sufficiently large value of negative voltage to prevent electrons passing from the region of the cathode 21 into the positive electric fields of the focusing electrode 23 and the accelerating electrode 24.

The occurrence of a pulse of voltage at the output of the amplifier 32, in response to an input pulse of voltage of unknown magnitude from an electrical device, such as the ionization chamber 28, causes such a voltage to be applied to the discriminator 36 and to the deflecting plate 26 of the electron gun. The discriminator 36, in addition to being constructed to apply the normal cut-off bias to the control grid 22, is also constructed to remove the bias voltage momentarily at the peak voltage of the input pulse of voltage. Thus the electrons in the region of the cathode 21 are momentarily allowed to pass through the control grid 22 and into the electric fields of the focusing electrode 23 and the accelerating electrode 24. Since the output pulse of voltage of the pulse amplifier is negative and is impressed

on the deflecting plate 26, the electric fields of the two deflecting plates 26 and 27 are in opposition and the deflection of the electron beam by the deflecting plate 27 will be altered in accordance with the peak value of the voltage pulse at the deflecting plate 26. Thus it will be seen that the electron beam will be deflected to impinge on the target 17 corresponding to the value of the peak voltage. The electron beam current at the target 17 is then amplified through the corresponding amplifier 71 to operate the corresponding register 72.

From the foregoing, it is apparent that each pulse of voltage will be accurately and proportionately recorded on a register 72 such that each count of that register 72 represents a pulse of voltage of a certain height. The proportionality mentioned arises from the use of the amplifier 32 in the signal input circuit.

Numerous uses of the present invention are obvious and one such use has been presented herein by showing the ionization chamber 28 as the source of voltage pulses. By using the ionization chamber 28, it is possible to determine the energy levels of the particles of radiation to which the chamber has been exposed.

While the salient features of the present invention have been described in detail with respect to one embodiment, it will, of course, be apparent that numerous modifications may be made within the spirit and scope of the invention, and it is therefore not desired to limit this invention to the exact details shown except in so far as they may be defined by the following claims.

What is claimed is:

1. A pulse analyzer for sorting and counting pulses of voltage comprising an evacuated envelope having an electron gun disposed at one end thereof, means for supplying operating voltages to said electron gun, means for normally maintaining said electron gun inoperative, means responsive only to the peak value of a pulse to be analyzed for rendering said electron gun operative to project an electron beam therefrom, means for deflecting said electron beam in accordance with said pulse, and means for determining the degree of deflection as a function of the peak value of said pulse.

2. A pulse analyzer for sorting and counting pulses of voltage comprising an evacuated envelope, an electron gun disposed at one end of said envelope, a plurality of similar target means mounted centrally at the other end of said envelope in a pair of linearly spaced-apart and alternately staggered rows and disposed transversely of the axis of said electron gun to provide a continuous series of separate target means, means for energizing said electron gun whereby an electron beam is generated, means for normally biasing said electron gun at cut-off, means responsive only to the peak value of a pulse to be analyzed for removing said normal bias at such value, means for deflecting said electron beam in accordance with said pulse, and means connected to said targets for indicating the particular target which intercepts said deflected beam.

3. A pulse analyzer for sorting and counting pulses of voltage comprising a substantially conical evacuated envelope, an electron gun having a cathode, control grid, focusing electrode, accelerating electrode, and deflecting plates disposed axially in spaced-apart relation at the converging end of said envelope, a plurality of simi-

lar targets centrally mounted at the other end of said envelope, said targets being disposed in two linear rows spaced apart along the axis of said electron gun and transverse thereto, the targets of each row being spaced apart substantially the width of one of said targets with the targets of one row alternately staggered with respect to the other to provide a continuous series of separate targets, means connected to said electron gun for supplying operating voltages thereto, means for normally maintaining said control grid negative to prevent a flow of electrons through said electron gun, means for supplying a pulse to be analyzed to one of said deflecting plates and at the peak value thereof to said control grid whereby the negative bias on said control grid is removed and the resulting electron beam deflected, and means for indicating which of said targets intercepts said electron beam as a function of the peak voltage of said pulse.

4. A pulse analyzer for sorting and counting pulses of voltage comprising a substantially conical evacuated envelope, an electron gun having a cathode, control grid, focusing electrode, accelerating electrode, and deflecting plates disposed axially in spaced-apart relation at the converging end of said envelope, a plurality of similar targets centrally mounted at the other end of said envelope, said targets being disposed in two linear rows spaced apart along the axis of said electron gun and transverse thereto, the targets of each row being spaced apart substantially the width of one of said targets with the targets of one row alternately staggered with respect to the other to provide a continuous series of separate targets, electrical means for supplying operating voltages to said electron gun, a source of pulses to be analyzed, means for amplifying said pulses, means for normally biasing said control grid sufficiently negative to prevent an electron beam being formed by said electron gun, said biasing means also being connected to the output of said amplifier and including means responsive to the peak value of said amplified pulse to remove said normal bias, means connecting the output of said amplifier to one of said deflecting plates to deflect the electron beam to one of said targets, and means for indicating the particular target which intercepts said deflected beam.

5. A pulse analyzer for sorting and counting

5 6 pulses of voltage comprising a substantially conical evacuated envelope, an electron gun having a cathode, a control grid, focusing electrode, accelerating electrode, and deflecting plates disposed axially in spaced-apart relation at the converging end of said envelope, a plurality of similar targets centrally mounted at the other end of said envelope, said targets being disposed in two linear rows spaced apart along the axis of said electron gun and transverse thereto, the targets of each row being spaced apart substantially the width of one of said targets with the targets of one row alternately staggered with respect to the other to provide a continuous series of separate targets, electrical means for supplying operating voltages to said electron gun, a source of pulses to be analyzed, means for amplifying said pulses, means for normally biasing said control grid sufficiently negative to prevent an electron beam being formed by said electron gun, said biasing means also being connected to the output of said amplifier and including means responsive to the peak value of said amplified pulse to remove said normal bias, means connecting the output of said amplifier to one of said deflecting plates to deflect the electron beam to one of said targets, and an electromechanical register connected to each of said amplifiers for recording the number of pulses as a function of peak voltage.
